DESIGN FOR A SCAFFOLD END FRAME

Roy M. Norton, Port Huron, Mich., assignor to
The Safway Steel Scaffolds Co. of Wisconsin,
Wauwatosa, Wis., a corporation of Wisconsin

Application March 29, 1939, Serial No. 83,903
In Canada March 16, 1939

Term of patent 14 years

To all whom it may concern:

Be it known that I, Roy M. Norton, a citizen of the United States of America and a resident of Port Huron, in the county of St. Clair and State of Michigan, have invented a new, original, and ornamental Design for Scaffold End Frames, of which the following is a specification, reference being had to the accompanying drawing, forming a part thereof.

In the drawing:

Fig. 1 is a front elevational view of a scaffold end frame showing my new design;

Fig. 2 is a side elevational view of the end frame shown in Fig. 1; and

Fig. 3 is a top view of the scaffold shown in Figs. 1 and 2.

I claim:

The ornamental design for a scaffold end frame, as shown.

ROY M. NORTON.
